EXTENSION TABLE

Thurlow E. McFall, Sparta, Mich., assignor to
Michigan Artercraft Company, Sparta, Mich.,
a corporation of Michigan

Application May 4, 1942, Serial No. 441,635

3 Claims. (Cl. 311—42)

This invention relates to extension tables and is primarily concerned with simple practical and novel improvements in extension tables of the type shown in my Patent No. 2,153,262 granted April 4, 1939.

The table of the above identified patent may be retracted to a very small compass, one main part of the table top being folded over two top parts which lie in the same horizontal plane, one of said parts being narrow compared to the remaining parts of the table top. The two lower top members or parts have a combined width equal to that of the other top member which is foldable to lie thereover in the retracted and small space occupying position of the table.

Such table has proven very practical and useful and has been largely manufactured and sold by the owner of the patent and licensees thereunder. It has been the endeavor to eliminate the narrow top member to which the wider top member is hingedly connected, and there has been devised the table construction shown in Patent No. 2,253,010 granted August 19, 1941, illustrating an extensible table top having two top members of the same width, one foldable to lie over the other in one position or turnable to lie in the same horizontal plane therewith. When unfolded to horizontal position the two top members may be brought into abutting relationship to form a table top or may be separated for the insertion of filler leaves between them.

Such construction shown in the last mentioned patent is greatly improved in the present application. In the construction shown in Patent No. 2,253,010 the hinges used permit relative movement of the foldable top member with respect to the under top member upon which it rests which may result in damage to the finish. The hinge construction used and the manner in which it is applied to the top members in the present invention eliminates loose or lost motion and the table devised is free of such defects and damage which might occur therefrom, perfecting the table so that it is a practical and commercial product. Various other improvements in structure make a perfected commercial table.

The invention may be understood from the following description taken in connection with the accompanying drawings, in which,

Fig. 1 is a plan view of the table in contracted and top folded position.

Fig. 2 is a plan view of the table extended to permit the upper top member to be turned

through an arc of 180° to lie in the same plane with the under top member.

Fig. 3 is a fragmentary vertical transverse section substantially on the plane of line 3—3 of Fig. 2 looking in the direction indicated by the arrows.

Fig. 4 is a plan view of the table extended to receive a filler leaf between the two main top members.

10 Fig. 5 is a perspective view of a hinge, a number of which are used for hingedly mounting the foldable top member.

Fig. 6 is a transverse vertical section through the upper part of the table in its contracted and 15 smallest space occupying position.

Fig. 7 is a view similar to Fig. 2 illustrating the first step in extending the table to position for the turning of the movable top member to lie in the same plane with the lower fixed top member.

20 Fig. 8 is a view similar to Fig. 7, with the foldable top member turned to lie in the same plane with and abutting against the under fixed top member.

Fig. 9 is a fragmentary section similar to Figs. 25 7 and 8, the two top members being separated with a filler leaf between, and

Fig. 10 is a fragmentary enlarged vertical section of the middle portion shown in Fig. 8, after the foldable top section has been turned to lie 30 in the same plane with the fixed top section and before they have been brought into abutting engagement.

Like reference characters refer to like parts in the different figures of the drawings.

35 In the construction of the table a horizontal top member 1 is provided which is supported by corner legs 2 between which is a vertical rail 3, side rails 4 extending from the legs 2 underneath the ends of the top member 1. Said top member 40 1 is permanently secured to the parts 3 and 4 and the legs.

The other top member 5 is preferably of the same size and outline as the fixed top member 1 and is adapted to lie directly over and against 45 the top member 1 in the folded position of the table, as in Fig. 6. When it is turned to a horizontal position in the same plane with the fixed top member 1, it is carried by two spaced corner legs 6 between which is a rail 7 similar to the

50 rail 3, with side members 8 extending underneath the end portions of the top member 5 and which are connected to the legs 6 and to the rail 7, and are also secured together by a horizontal cross board 9 as shown.

55 To the side members 8 one of the end slides

of two series of extensible slides are connected. Each of the extensible slides includes center slide members 10 slidably connected with slide members 11 and 12 at one side and 11a and 12a at the other side, the members 12a being permanently secured to the under side of the top member 1. The slide members 12 lie inside of and are secured to the side parts 8 as shown. The detail of the extensible slides need not be described as such detail is old and well known in extension slides for tables.

The foldable top member 5 at its inner edge has hinged connection to the outer ends of the center slides 10 through a connection cross bar 13 secured to and extending between said center slides 10. Each of the hinges used is a modification of the well known concealed hinge known as the Soss hinge. Such hinges, in Fig. 5, show an upper hinge member made of sheet metal having a part 14 of U-shape in cross section, attaching ears 15 turned oppositely from one end of each of the sides of the U, and said sides of the U provided with inclined grooves at their inner sides made by pressing out opposite ribs 16. In the regular Soss hinge, the lower member of the hinge is of the same construction, but with my invention the lower member includes a part 17 of sheet metal of U-shaped cross section, the sides having the grooves provided in the same manner by the outwardly pressed ribs 18. Attaching ears similar to the ears 15 on the upper member are not provided with my invention, but the bottom of the hinge member 17 is extended a short distance and widened as at 20 and then turned downwardly at right angles, as indicated at 21. The two hinge members 14 and 17 are connected together by a plurality of links 19 which are all pivotally joined together between their ends, alternate links having pivotal connection at one end to the hinge members 14 and 17 respectively, the other ends of said links having pins extending therethrough which traverse the grooves made by the ribs 16 and 18.

With my invention the hinge parts 14 are inset at the inner edge of the top member 5 and secured by screws passing through the ears 15 in the usual manner of attaching concealed hinges of the type described. The other members 17 of the hinges used are connected to and at the outer vertical side of the bar 13 by means of screws passing through the parts 21.

Linkage consisting of two links 22 and 23 are pivoted together at 24 at adjacent ends. The other end of the link 22 has pivotal connection to the board 9 and that of the link 23 to the under side of the bar 13. The first step on enlarging the table is to move the legs 6 and the parts 7, 8 and 9 connected therewith outwardly as in Fig. 7, the slides 11 and 12 being extended, as in Fig. 2, until links 22 and 23 are in alignment. Any further outward movement will cause the aligned links to pull upon the bar 13 whereupon the slides 10 and 11a will be extended as indicated in Fig. 9.

In practice when the table is to have its stop enlarged without using any filler leaves the extension is as in Fig. 2, whereupon the top member 5 may be as in Fig. 2 or Fig. 7, and may be turned through 180° to the position shown in Fig. 8; or the extension may be slightly farther than shown in Fig. 2 with a separation of the top members 1 and 5 a short distance, as in Fig. 10, with a moving of the slides back so as to

bring the two top members 1 and 5 into abutting engagement.

For the greater extension it is desirable that the central portion of the table be supported.

For this purpose a board 25 extends between and at the under sides of and is connected to the center slide members 10, moving therewith. At the under side of the board a supporting leg may be mounted. Such leg may be centrally located midway between opposite sides of the table permanently secured to the board 25 and extend downwardly therefrom. Preferably, it will be of the folding type shown at 26, the detail of which is not described as it is fully set forth in a pending application, Ser. No. 417,612 filed November 3, 1941, as an improvement of Patent No. 2,268,042 granted December 30, 1941.

The inner edge of the top member 1 is recessed at 27 to provide openings to receive the parts 17 of the hinges when the table is folded and the table is in its smallest space occupying position (Fig. 6), or when it is unfolded and no fillers used, as in Fig. 8. The upper edge of the cross rail 7 is likewise provided with shallow recesses 28 to provide space for the horizontal sections 20 of the lower hinge members when the table is in its smallest space occupying position (Fig. 6). The filler or fillers 29 at one edge likewise are provided with recesses, like the recesses 27, in the top member 1 for the entrance of the hinge parts 17 as shown in Fig. 9.

The construction is sturdy and one in which the parts 17 of the hinges are held in all directions against any loose or aimless movement, in effect substantially the same as though the hinge parts 17 were securely connected with the top member 1. In such position of the hinges the movable top member 5 may be folded into the positions shown in either Fig. 6 or Fig. 8 without lateral movement of the movable top member with respect to the under top member, guarding against rubbing of the contacting finished sides of the two top members against each other which might mar or deface such finish. The construction described is particularly practical, useful and economical, may be manufactured at low cost, is durable in service and is thoroughly commercial in all respects. It does away with the narrow top member to which the foldable top member is hinged in my previous Patent No. 2,153,262, costing less to build and avoiding the double division which is inescapably present in the table top of my previous patent when no filler leaves are used. In the patent, No. 2,253,010 looseness of connection and instability is overcome and removed by the snug reception in the socket recess 21 of the parts 17 of the hinges.

The invention is defined in the appended claims and is to be considered comprehensive of all structures coming within their scope.

I claim:

1. In a table, two groups of extensible slides, a top member permanently secured to one of the end slides of each of said groups, a second top member, two-part hinges connecting said second top member with an intermediate slide member of each group, a supporting structure connected to the other ends of said extensible slide groups, said fixed top member being provided with recesses at an edge and the parts of said hinges connected with said intermediate slides having projecting portions to enter said recesses in which position the hinged top member may be turned to lie over and against the fixed top member or lie in the same plane therewith, as specified.

2. In a table, two horizontal extensible sections having supporting legs at their outer portions, a horizontal top member permanently secured over one of said sections, a second top member having hinges at one edge and hingedly and movably mounted with respect to the first top member, said first and second top members having edge abutting engagement in one position, the second top member being supported by outward extension of its associated section, and said second top member being also adapted to be turned on its hinges through an arc of substantially 180° to lie over and against the first top section, in which position the supporting legs therefor may be moved underneath said superimposed top sections, said hinges having projections and the fixed top section having recesses to receive said projections to stabilize the said top sections with respect to each other during said turning move-

ment and after the second top member is superimposed over the first top member.

3. In a table top, two groups of extensible slides each comprising a plurality of slide members, 5 a top member permanently secured to one of the end slides of each of said groups of slides, a second top member of the same dimensions as the first top member, hinges connecting the second top member with an intermediate slide of each 10 group, said hinges each comprising two hinge members, one inset at the inner edge of the second top member and the other having a portion within the inner edge of said first top member when the top members are in superimposed relation and having means connected with said intermediate slide members, said fixed top member having recesses to receive said portions of the hinge parts located within its inner edge.

THURLOW E. McFALL.
